UNITED STATES PATENT OFFICE.

HALCOLM ELLIS, OF NEWARK, NEW JERSEY.

TYPE-BASKET SHIFT FOR TYPEWRITERS.

Original application filed February 5, 1919, Serial No. 275,118. Divided and this application filed February 19, 1923. Serial No. 620,088.

To all whom it may concern:

Be it known that I, HALCOLM ELLIS, a citizen of the United States, residing at Newark, in the county of Essex and State of New Jersey, have invented certain new and useful Improvements in Type-Basket Shifts for Typewriters, of which the following is a specification.

This invention relates to that class of typewriters of the standard, as distinguished from the portable, type having a shiftable basket carrying the type bars and it pertains to improved lost motion shifting means for the type basket segment and limiting means whereby the exact limits of movement of the type basket segments are insured without reference to the extent of depression of the shift key.

The present application is a division of my Patent No. 1,446,388, Feb. 20, 1923.

In those typewriters having a shiftable type basket, when it is desired to print a capital letter, the shift key is depressed, causing the type basket and type bars to be elevated sufficiently to bring the lower type on the type block into printing position, the carriage meanwhile remaining stationary. This type of typewriter has the advantage of enabling a simple and firm carriage to be used, promotes good type alignment, obviates the necessity of using the counterbalancing springs required with a shifting carriage, and produces the same shift key touch with a carriage of any length.

My present invention, embodying an improved lost motion shifting means comprising, in part, a spring device, insures the elevation of the type basket to its full limit and yet the type basket will not move past the proper position for printing a capital letter or any lower case type even though the shift key is depressed further than necessary. The lost motion means compensates for unnecessary movement of the shift key without placing any of the parts under strain or requiring heavy touch of the finger.

While the present improvements are illustrated in connection with a typewriter, such as disclosed in my aforesaid patent, this is done for the purpose of disclosing a practical embodiment of the invention and relationship to the parts of a typewriter and not by way of limitation of the inven-

tion as the latter may be used on any typewriter employing a shiftable basket or segment carrying the type bars.

The invention is susceptible of modification and is not limited to the specific embodiment described hereinafter and disclosed in the drawing.

In the accompanying drawings,

Figure 1 is a vertical longitudinal section through a typewriter provided with my present improvements;

Fig. 2, a detail front elevation of the basket segment, showing the stops which limit the vertical play of the latter;

Fig. 3, a detail perspective of the shift keys and means for raising the basket-segment, and

Fig. 4, a detail cross section of the lost motion connection of the basket-segment shifting means.

The key levers are shown at 1, the operating connections for the type bars appear at 7, 8, 9 and 13, and the type bars appear at 12. The type bars are mounted in the vertically shiftable type basket or segment 15 on a pivot wire 11.

The type basket 15 is of segmental form having vertical guides or ways 16 mating those shown at 17 on the machine frame. Ball bearings 18, Fig. 2, may be employed. The upper and lower limits of movement of the type basket segment are determined by adjustable stops 19 on the machine frame and adjustable stops 20 on the type basket segment 15.

Carried by a shaft 32 are two shift key levers 33. Loose on shaft 32 is an arm 34 having a hub 35 which has a pin-and-slot connection 36 with shaft 32. Fixed on shaft 32 by a set screw is a collar 37. A coil spring 38 surrounding shaft 32 has its respective ends fastened to the hub 35 and collar 37, said spring being under such tension that it is adapted to keep the pin-and-slot connection engaged when the key 33 is depressed. The depression of either key 33 moves the arm 34 and elevates the type basket segment 15 until the latter is arrested by the contact of the stops 20 with the upper stops 19. Further depression of the key 33 will not swing the arm 34 any further but only place an additional tension on the spring 38, whereupon the pin-and-slot connection will yield.

A shift key lock is provided which com-

prises a small cam 39 having a key type at its upper end and pivoted on the side frame of the machine. This cam bears on a pin 40 on the left-hand key lever 33. The depression of the key will turn the cam 39 in such a way as to depress the key lever 33; and its return spring 41 is so light that it will not overcome the friction of the parts moved by the keys 33, but a slight depression of either key 33 will relieve this friction on the shift key lock which will then be returned to its normal position by spring 41.

What I claim is:

1. In a typewriter, the combination with a shiftable type basket, and means for limiting its play, of a pair of operating key levers for shifting the type basket, a shaft to which said key levers are connected, the key levers and shaft comprising a unitary

structure, a lifting arm for the type basket, 20 and a spring-tensioned lost-motion upright connection between the shaft and the arm.

2. In a typewriter, the combination with a shiftable type basket, and means for limiting its play, of a pair of operating key levers for shifting the type basket, a shaft to which said key levers are connected, the key levers and shaft constituting a unitary structure, a lifting arm for the type basket, 25 said arm being rockably mounted on the shaft, and a coil spring connected to the arm and to the shaft, said spring encircling the shaft, 30 said spring constituting a lost-motion connection between the arm and the shaft.

In testimony whereof I affix my signature,

HALCOLM ELLIS.
